UNITED STATES PATENT OFFICE.

FREDERICK W. WERNER, OF DENVER, COLORADO.

COLLAR-BUTTON.

1,255,254.

Specification of Letters Patent.

Patented Feb. 5, 1918.

Application filed February 12, 1916. Serial No. 77,936.

To all whom it may concern:

Be it known that I, FREDERICK W. WERNER, a citizen of the United States of America, residing at the city and county of Denver and State of Colorado, have invented 5 a new and useful Collar-Button, of which the following is a specification.

My invention relates to improvements in collar buttons, and the objects of my invention are:

First, to provide a collar button that is expressly adapted for buttoning the front ends of the collar to the front of the neck band of the shirt.

Second, to provide a collar button that is provided with any suitable kind of commonly used inner shirt band engaging base and shank portion, but that is provided with an easily grasped anchor bar or head for securing the front ends of the collar and the back of the collar to the neck band of the shirt, the said button being especially adapted for use in connection with turn down collars of a style in present use, in which the proximity of the opposing edges of the fold of the collar, renders the buttoning of the collar extremely difficult, in connection with the ordinary style of collar button.

I attain these objects by the mechanism illustrated in the accompanying drawings, in which:

Figure 1, is a perspective view of the improved collar button.

Fig. 2, is a view thereof partly in side elevation and partly in section.

Fig. 3, shows the button in the collar band of an open front shirt, and in position to receive the first or inner button flap of the collar.

Fig. 4, is a front view showing the long end of the head of the button inserted through the button hole of the inner end or flap of the collar, which is the first step in the buttoning of the collar.

Fig. 5, illustrates the second step in the process in which the head is turned and its long end pressed to bring the short end thereof through the button hole.

Fig. 6, illustrates both flaps of the collar buttoned, and the head turned to prevent accidental unbuttoning. And

Fig. 7, is a vertical, sectional view taken centrally through the collar and shirt band, as shown in Fig. 6.

Similar letters of reference refer to similar parts throughout the several views.

Referring to the drawings:

The figure 1 illustrates a collar button embodying my invention. In this figure, as well as in the remaining figures of the drawings, the numeral 1 designates the shank of the button and 2 designates its inner holding base, which preferably is a round disk-shaped button, but which may be of any other shape, such as a cross bar, that will 60 keep the shank from working accidentally out of the button holes 3 in the shirt band 5 of the shirt. The shank and inner base member may be of any desired construction.

The essentially new and novel element of 70 my collar button resides in its head 6, which comprises a cross bar formed either integrally with or secured to the opposite end of the shank from its base and forms the front display end of the collar button, and which 75 secures the free ends of the collar to the shirt.

This head portion of my collar button is in the form of a flat bar, but it may be any kind or form of cross section of a cross bar, 80 and its front surface may be ornamented by any kind or character of embellishments. This cross bar head, however, is of a peculiar and novel construction and it is constructed and arranged as follows:

The middle portion of the cross bar is arranged at right angles to the shank of the button and the cross bar is made in two unequal lengths 7 and 8; the long portion of the cross bar is the finger grasping portion 90 of the cross bar and it is the first to be inserted in the button holes of the collar after, of course, the head and the shank have been placed through the button holes of the shirt band. And in order that it may readily be 95 grasped with the fingers and be quickly inserted in the button holes of the shirt and collar, its long end 8 is bent outwardly and in an outward curved form far enough to enable it to be easily manipulated and 100 pressed by the fingers of the operator. The extremity of the long end 8 is also preferably flattened and made wider than its remaining portion, and is given an oval form, as shown, in order to facilitate its insertion 105 in a button hole.

The short end 7 of the cross bar extends preferably at right angles to the shank of the button, and it is preferably of about one-half of the length of the curved member 8 110 of the button, and its outside surface is preferably tapered down from the shank to its

outer end, the inside surface of which is flat and bears flatly against the ends and the back of the collar.

Both portions of this cross bar head portion of my collar button are made of a width that will enable them to be easily and quickly inserted in the button holes of the shirt and of the collar, and at the same time securely hold and button the collar to the shirt.

10 The method of manipulating the button in buttoning a collar is as follows:

15 The long end 8 of the head of the collar button is inserted in the button hole of the inner end of the collar band of the shirt, and then turned to a horizontal position with the said long end next the vertical edge of the band; the said long end is then pressed upon, which causes the short end 7 to pass through the button hole. The head is then turned to a vertical position with the long end down, and the said long end is passed through the button hole in the outer end of the collar band and again turned to a horizontal position with the said long end next the vertical edge of the said outer end of the collar band, and is then pushed inward, which brings the short end of the head through the button hole after which the head is turned to the position shown in Fig. 3. The collar is then buttoned to the back of the collar band and its inner free end is positioned so that the button hole therein will pass over the long end of the head, and the head is then turned to the position shown in Fig. 5, and the long end thereof pressed to cause its short end to pass through the button hole, after which the head is again turned to the position shown in Fig. 3. The

remaining free end of the collar is then 40 passed under the fold or wing of the buttoned end, and the hole therein is passed over the long end of the head, which is then turned to a horizontal position, but pointing in the opposite direction to that shown in 45 Fig. 5, and after pressing the said long end inward to cause its short end to pass through the button hole, the head is again turned to the position shown in Fig. 6, in which position both ends of the collar are securely 50 fastened, as will be understood by reference both to Figs. 6 and 7.

Having described my invention, what I 55 claim as new and desire to secure by Letters Patent, is:

The combination in a collar button, of a base, a shank round in cross section, and a head in the form of a flat bar, one end portion of which is outwardly curved and gradually reduced in thickness, and terminates in 60 a blunt button-hole-inserting point, the said head tapering from its button-hole-inserting portion where it is widest, to its opposite end where it is narrowest, the portions of the head on each side of the shank being of unequal length, the curved end portion being made the longer, whereby when the curved end is inserted in a button-hole and the head turned to stand parallel with the said hole, the shorter portion of the head is passed through the hole by pressing on the said curved end.

65 In testimony whereof I affix my signature in presence of two witnesses.

FREDERICK W. WERNER.
